A. C. POTTER,
ORCHARD HEATER OR SMUDGE POT.
APPLICATION FILED DEC. 11, 1920.

1,394,218.

Patented Oct. 18, 1921.

UNITED STATES PATENT OFFICE.

ARTHUR C. POTTER, OF MISSION, TEXAS.

ORCHARD-HEATER OR SMUDGE-POT.

1,394,218.

Specification of Letters Patent.

Patented Oct. 18, 1921.

Application filed December 11, 1920. Serial No. 429,947.

To all whom it may concern:

Be it known that I, ARTHUR C. POTTER, a citizen of the United States, residing at Mission, in the county of Hidalgo and State 5 of Texas, have invented certain new and useful Improvements in Orchard-Heaters or Smudge-Pots, of which the following is a specification, reference being had to the accompanying drawings.

10 The purpose of the present invention is to provide an improved draft flue and damper carried by a cap especially adapted for use in connection with heaters or crude oil smudge pots, which are commonly used 15 in various orchards during frosty weather, particularly in citrus fruit orchards.

Considerable inconvenience and trouble has been experienced with various devices of this kind now in use, for the reason that 20 when the draft is opened enough for proper service, the flame from the smudge pot or heater will readily blow out, especially in windy weather. Therefore, the present invention aims to provide a draft flue and 25 damper to withstand the most severe and erratic winds, the damper capable of being opened to suit any temperature, without impairing its efficiency in protecting the draft.

A still further purpose is the provision of 30 a heater or draft flue and damper carrying cap, wherein the draft flue is detachable as well as the damper, and the damper may be adjusted to any desired position relatively to the opening in the wall of the cap 35 and relatively to the passage through the flue, so as to govern the draft in its passage into the chamber of the draft flue and thence through the cap.

As a further purpose the invention aims 40 to provide means for fastening the chamber and the draft flue to the wall of the cap.

While the design and construction at present illustrated and set forth is deemed preferable, it is obvious that as a result of 45 a reduction of the invention to a more practical form for commercial purposes, the invention may be susceptible of changes, and the right to these changes is claimed, provided they are comprehended within the 50 scope of what is claimed.

The invention comprises further features and combination of parts, as will be herein-after set forth, shown in the drawings and claimed.

55 In the drawings:—

Figure 1 is a view in elevation of the im-

proved orchard heater or smudge pot, showing the cap with the improved draft flue and damper applied.

Fig. 2 is a vertical sectional view through the cap, the flue and the damper.

Fig. 3 is a cross sectional view on line 3—3 of Fig. 2.

Fig. 4 is a vertical sectional view similar to Fig. 2 showing a modified construction 65 of fastening for the draft flue and damper to the cap.

Fig. 5 is a cross sectional view on line 5—5 of Fig. 4.

Referring more especially to the drawings, 1 designates a conventional form of smudge pot or heater, particularly of the crude oil type, wherein the fluid, such as crude oil is placed for burning purposes, and the upper part thereof terminates in a 75 marginal flange 2; and 3 denotes a cap to engage the smudge pot or heater. This cap is preferably frusto-conical in contour, though it may be of any other suitable shape, and its lower larger end terminates 80 in an angular flange 4, a portion of which extends into the pot or heater, so as to support the cap upon the heater. The cap has its upper smaller end connected in any suitable manner, such as indicated at 5 to 85 an elongated flue 6. It is seen that this flue is broken at the point indicated, thereby indicating that the flue 6 may be of any length desired. The wall of the cap is provided with an opening 7, and secured in any 90 suitable manner, preferably by spot welding or brazing at such points as indicated at 8 is an angular flange 9. This flange 9 is arranged on the side of the cap and extends up adjacent the opening 7. It will be noted 95 that the flange 9 is preferably angular in contour, and in fact has downwardly diverging portions. The upper parts of this angular portion or guide flanges are connected by a transverse portion 10. The side 100 guides of the flange 9 are engaged by the angular flanges 11 of the flue 12. The flanges 11 of the flue 12 may be securely frictionally engaged with the guide flange 9, and in such a manner that under any 105 ordinary conditions the flanges 11 cannot be moved, or the flue 12 cannot be moved.

The flanges 11 are formed on the sides of the flue 12 as extensions of the sides, and due to constructing these flanges angular, 110 rabbets or longitudinal recesses 13 are caused to be formed on the sides of the flue

12. By so constructing the guide flanges 11, and providing the guide recesses 13, it will be noted that a slide or damper 14 may engage therewith, and regulated to control 5 the draft in its passage through the opening 7. The damper or closure 14 carries a knob 15, and due to the slide or damper 14 being mounted in the rabbets 13 so as to move, it is capable of being adjusted relatively to 10 the opening 7, in order to govern the air in its passage through the flue and thence through the opening 7, and finally out through the cap and the flue 6, which is attached to the frusto-conical cap. It will be 15 noted that the flue 12 is semi-cylindrical in cross section, and in side elevation it is somewhat frusto-conical shaped, as shown clearly in Fig. 1. The upper end of the flue 12 is provided with a top flange 16, the flange 17 of which engages the flange above 20 the opening 7, thereby assisting in holding the flue in place and preventing the escape of air.

In order to control the draft through the 25 flue 12, the operator may grasp the handle of the damper between the flue and the side walls of the cap or heater, and move the damper so as to control the draft through the opening 7.

30 In Figs. 5 and 6 a different form of guide flanges for the flue on the cap are provided. These guide flanges are of one piece of sheet metal, and it is to be noted that the flue and the damper are capable of movements or detachment independently of each other. Namely, the damper may be detached without disturbing the flue, and also the flue can be changed without disturbing the position of the damper, whereas in the 35 other figures the damper 14 can be removed without disturbing the flue, but in this form should the flue be removed, the damper is likewise removed. While the connections of the flue and the damper may be 40 of any general construction, it is obvious that the best results are obtained by the particular form or construction of flue and damper herein shown.

The top 16 may be spot welded or brazed, 45 or otherwise secured to the upper end of the flue.

The damper or slide 14 frictionally en-

gages between the outer face of the cap and the opposite wall of the rabbets 13, so as to hold the damper or slide 14 frictionally in 55 position, when adjusted.

The invention having been set forth, what is claimed as being useful is:

1. In an orchard heater, a cap adapted to be operatively supported upon an orchard heater or smudge pot, and provided with an opening, a flue connected to the upper end of the cap, a flue disposed adjacent the side of the cap, said side flue having a communicating opening with the interior of the cap, a damper mounted in guides and adapted to control the draft through said opening, and means for fastening the flue and the damper detachably and movably in position. 60

2. In an orchard heater, a heater or smudge pot, a cap operatively mounted upon said pot and having its upper end connected to a flue, said cap having an opening in its side wall, an adjustable damper for said opening, an elongated flue arranged on the cap and having one end registering with the opening and extending downwardly and slightly outwardly relatively to the heater or pot, whereby the 75 draft may be drawn up thereinto and enter the cap or flue.

3. In a heater, a heater or smudge pot, a frusto-conical cap operatively supported on the pot, a flue connected to the upper 80 end of the cap, the wall of the cap having an opening, a damper therefor, a flue with a tapering contour and being semi-circular in cross-section having one end closed and the sides of the flue arranged adjacent the 85 side of the cap, said last mentioned flue being engaged over the opening in the cap, guide flanges on the side of the cap on opposite sides of the opening and at the top, the sides of the last mentioned flue 90 having extension flanges engaging the guide flanges of the cap, so as to hold the flue over the opening, the flanges of the sides of the last mentioned flue having guide rabbets for the reception of the damper 95 100 which covers the opening.

In testimony whereof I hereunto affix my signature.

ARTHUR C. POTTER.
